UNITED STATES PATENT OFFICE

WILLIAM B. MACMILLAN, OF ABBEVILLE, LOUISIANA, ASSIGNOR TO LOUISIANA STATE RICE MILLING COMPANY, INC., OF ABBEVILLE, LOUISIANA, A CORPORATION OF LOUISIANA

DESIGN FOR A CARTON

Application filed September 7, 1929. Serial No. 32,686. Term of patent 14 years.

To all whom it may concern:

Be it known that I, WILLIAM B. MACMILLAN, a citizen of the United States, residing at Abbeville, in the parish of Vermilion and State of Louisiana, have invented a new, original, and ornamental Design for Cartons, as shown in the accompanying drawing, forming part of this specification.

In the drawing:—

Figs. 1 and 2 are perspective views of the carton of my new design taken from opposite sides, the top of the carton being shown in Fig. 1 and the bottom in Fig. 2.

Fig. 3 is a front elevation of the carton.

I claim:

The ornamental design for a carton substantially as shown.

Dated August 31st, 1929.

W. B. MACMILLAN.
